UNITED STATES PATENT OFFICE.

WILLIAM F. GEHRIG, OF BERKELEY HEIGHTS, NEW JERSEY.

TOY PISTOL.

Application filed August 18, 1924. Serial No. 732,713.

This invention relates, generally, to improvements in toy pistols; and, the present invention has reference, more particularly, to a novel and simply constructed toy-pistol 5 to be used in firing paper-caps or fulminates.

The present invention has for its principal object to provide a toy-pistol in which the parts, which have been reduced to a minimum, so as to cheapen the cost of construction, are easily and quickly assembled; and, the said invention has for its further object to provide in connection with the main shell or casing of the pistol, means for properly inserting and maintaining the usual band or strip of paper-caps or fulminates in place 15 within the pistol, and to provide a paper-strip engaging means actuated by the trigger of the pistol, for actuating the exploding or striking hammer, and to intermittently feed the paper-strip containing the spaced fulminates in proper position upon the anvil of the pistol and in front of the striker-head of the hammer, the paper-strip being moved only when the paper-strip engaging means is 20 brought into engagement with the protuberance formed by the fulminates projecting from the face or faces of the strip.

The invention has for its further object to provide in connection with the anvil of a 30 toy-pistol, a guard which will prevent particles of the paper-strip and of the exploding fulminate from flying rearwardly toward the person holding the pistol, and to thereby prevent any possible injury to the 35 person while in the act of firing the pistol.

Other objects of this invention not at this time more particularly enumerated, will be more fully understood from the following detailed description of the said invention.

With the various objects of the present invention in view, the said invention consists, primarily, in the novel toy-pistol hereinafter set forth; and, the said invention consists, furthermore, in the novel arrangements and combinations of the various devices and parts, as well as in the details of the construction of the said parts, all of which will be more fully described in the following specification, and then finally embodied in 50 the clauses of the claims, which are appended to and which form an essential part of the said specification.

The invention is clearly illustrated in the accompanying drawings, in which:—

Figure 1 is a side elevation of a toy-pistol made according to and embodying the prin-

ciples of the present invention; and Figure 2 is an elevation of one of the casing-members of the pistol, showing the interior construction of the same. 60

Figure 3 is a side elevation of the toy-pistol, with one of the casing-members removed, to disclose the interior mechanism, the devices and parts thereof being represented in their normal initial positions; and 65 Figures 4, 5 and 6 are similar views, the devices and parts of the interior mechanism, being represented in their various active positions, before and after the cap or fulminate has been fired. 70

Figure 7 is a detail transverse vertical sectional representation of the pistol, said section being taken on line 7—7 in said Figure 5, looking in the direction of the arrows in said figure; and Figures 8 and 9 75 are perspective views of certain of the parts of the interior mechanism of the pistol.

Similar characters of reference are employed in all of the said herein-above described views, to indicate corresponding 80 parts.

Referring now to the several figures of the drawings, the reference-character 1 indicates one of the casing-members or shells, and 2 indicates the other and oppositely placed casing-member or shell of the pistol. In practice, the members or shells 1 and 2 are shaped to simulate in general appearance and outline, a magazine revolver or pistol, the hollow or chambered portions of the 90 casing-members or shells 1 and 2 being opposed with their hollow sides together, and then secured one to the other in any convenient and desirable manner, preferably by means of a screw, as 3, so that together they 95 provide a hollow or chambered casing, for the arrangement therein of the interior mechanism of the pistol. The said shells or casing-members are provided with marginally cut away portions so as to provide the 100 body of the pistol, produced by the assembled casing-members or shells with slots or openings, as 4, 5, 6 and 7, substantially as shown, and for the purposes to be presently 105 more fully set forth.

At their upper portions, adjacent to the slot or opening 4, the said casing-members or shells are made with suitably shaped extensions, as 8, back of which are re-enforcements 9. As will be evident from an 110 inspection of the drawings, these extensions provide the anvil 10 of the pistol, upon

which the caps or fulminates are adapted to be exploded. Surrounding portions of the anvil thus produced, are marginal walls 11, providing suitable safety-guards, and forming an exploding chamber 12, which is open toward the front, as at 13, and has a means of communication, as at 14, with the main chamber of the pistol, as will be clearly evident from an inspection of Figures 2, 3, 4, 5 and 6 of the drawings. At suitable locations, the said casing-member or shell 1 is provided with pivot-posts 15 and 16 which project from the inner face of the said member or shell, across the main chamber 15 of the pistol, and terminate, respectively, in oppositely located holes or perforations 17 and 18, with which the other casing-member or shell 2 is provided. The said casing-member or shell 1 is also provided with other posts 19 and 20, and also with a lug or projection 21. Disposed between the side-walls 22 and 23 of the casing-member or shell 1 is a resilient member or spring-plate 24, provided with a suitably bent portion, as 25, which is arranged about the post 20, to cause the flat end-portion 26 of the said member or spring-plate to bear lightly against an inserted strip 27 provided with the usual distribution of caps or fulminates 28. The tension of said end-portion 26 of the plate 24 is such, that it will not interfere with the movement of the strip toward the anvil 10 of the pistol, but will at all times maintain the proper flat relation of the strip, and will prevent any buckling of the strip, during its movement toward the anvil. Connected with and extending forwardly from the said end-portion 26 of the resilient member or spring-plate 24, through the previously mentioned opening 7, is a suitably formed fingerpiece or push-member 29, for forcing the said end-portion 26 away from contact with the face of the side-wall 23, so as to permit of the insertion and the proper positioning of the proper-cap or fulminate-carrying strip 27, as will be clearly evident. Pivottally mounted upon the post 15 is a trigger-member or element 30 comprising a fingerpiece 31 which extends into and through, and is movably disposed in the opening 5, for actuating the trigger. The said trigger-member or element 30 is also provided with an actuating arm 32 which is provided with pivot-lugs or pins, as 33, extending on opposite sides of the free end-portion of the said arm. As shown more particularly in Figure 8 of the drawings, there is oscillatorily mounted upon the said lugs or pins 33, the members 35 and 36 of a yoke-shaped push-member or element 34, one of its members, as 35, being marginally cut away in a straight line, as at 37, said marginally cut-away portion normally being in engagement with and resting upon the upper surface of the stop-lug or pro-

jection 21, this normal relation of these parts being produced by the action of a trigger-controlling spring, having a coiled-portion 38 encircling the post 15, an arm-portion 39 bearing against the post 19, and another arm-portion 40 extending between the said members 35 and 36 and bearing upon one of the said lugs or pins 33, as will be understood from an inspection of Figures 3, 4, 5 and 6 of the drawings. The main purposes of the said trigger-spring are to return the trigger into its normal initial position after it has been pulled and then released by the operator, and to maintain the push-member in its lowest position upon the stop-lug 21, due to its pivotal connection with the trigger, as indicated in Figure 3.

Oscillatorily disposed upon the post 16 is a suitable shaped hammer-arm 42, the upper portion of which extends into and through 85 and is movable in the opening or slot 4, the said arm being provided with a rearwardly projecting portion 43 having a hammer-head, as 44, upon its free end, which normally rests upon the anvil 10. Co-operating 90 with said hammer-arm is a lift-plate 45, made of sheet-metal, and which is securely affixed to said hammer-arm by a flanged portion 46 turned over the marginal portion 47 of the hammer-arm, and a tongue 95 or lug 48 struck up from said lift-plate 45, said tongue or lug being bent at a right angle to said plate and being inserted and secured in a hole or perforation 49 with which the hammer-arm 42 is provided, as 100 clearly indicated in said Figures 3, 4, 5 and 6. The normal initial position of the said hammer-arm 42 and the lift-plate 45 is produced by a hammer-controlling spring having a coiled portion 50 encircling the post 16, an arm-portion 51 bearing against the post 19, and another arm-portion 52 bearing against the flanged portion 46 of the lift-plate 45, or upon the hammer-arm, as will 110 be clearly evident. The purpose of the lift-plate 45 will be fully understood from an inspection of Figures 4 and 5, from which it will be seen that when the marginal edge 53 of the push-member 34 rides against the marginal edge 54 of the lift-plate 45, the 115 hammer-head 44 will be raised away from the anvil 10, against the action of the hammer-controlling spring, so that the uppermost cap or fulminate is located directly in front of the anvil, as shown in said Figure 120 5. As soon, however, as the marginal edge 53 of the push-member 34 rides past the corner 55 of the lift-plate 45, then the hammer-controlling spring exerts itself and forcibly drives the hammer-head 44 down upon 125 the cap or fulminates in front of the anvil 10, thereby firing or exploding the same, as will be clearly understood from an inspection of Figure 6 of the drawings. The operator now releasing the pressure exerted 130

by his finger upon the trigger, the trigger-controlling spring will immediately return the trigger-member or element 30 and the push-member 34 to their normal positions, 5 with all the elements and parts of the pistol ready for the next firing operation.

From an inspection of said Figure 6 of the drawings, it will be seen that, as the cap or fulminate is exploded, that portion of the 10 paper-strip surrounding the said cap or fulminate is also consumed, and that the marginal walls 11 of the anvil 10 to serve as a guard, to prevent any particles of the paper or powder from flying in a rearward direction, so as to prevent any possible injury of the person handling the pistol.

Of course, I am fully aware that some changes may be made in the general arrangements and combinations of the various 20 devices and parts, as well as in the details of the construction of the said parts, without departing from the scope of the present invention as set forth in the foregoing specification, and as defined in the clauses of the 25 claims which are appended thereto. Hence, I do not limit my present invention to the exact arrangements and combinations of the devices and parts as described in the said specification, nor do I confine myself to the 30 exact details of the construction of the said parts, as illustrated in the accompanying drawings.

I claim:—

1. A toy-pistol comprising a pair of casing-members secured together to provide a chamber, means within said chamber for feeding a cap-containing strip to the firing-anvil of the pistol, and a flat spring-plate within said chamber, means for securing the 40 said spring-plate at one end-portion thereof in a fixed position, and the other end-portion of said spring-plate being adapted to bear upon the cap-containing strip to maintain the same in proper position, but arranged so 45 as not to interfere with the forward movement of the said strip, and a fingerpiece connected with and extending from said spring-plate to a point outside of the chamber of the pistol to permit of the spring-plate to 50 be forced out of contact with the cap-containing strip.

2. A toy-pistol comprising a pair of casing-members having marginal side-walls, said casing-members being secured together 55 to provide a chamber, a post extending from one of said casing-members, means within said chamber for feeding a cap-containing strip to the firing-anvil of the pistol, a flat spring-plate within said chamber, said 60 spring-plate having a bent portion in contact with said post and having its lower end-portion in retaining engagement with portions of the side-walls of the casing-members, and the other end-portion of said 65 spring-plate being adapted to bear upon the

cap-containing strip to maintain the same in proper position, but arranged so as not to interfere with the forward movement of the strip, and a fingerpiece connected with and extending from said spring-plate to a point outside of the chamber of the pistol to permit of the spring-plate to be forced out of contact with the cap-containing strip. 70

3. A toy-pistol comprising a pair of casing-members secured together to provide 75 a chamber, a trigger-member mounted within said chamber, and a cap-engaging means pivotally connected with said trigger-member, said cap-engaging means having a portion adapted to engage a raised cap of a cap-containing strip for intermittently feeding said strip in a forward direction, combined with a spring-tension within said chamber, said spring-tension having a portion in maintaining contact with the cap-containing strip, but arranged so as not to interfere with the forward movement of the said strip, and a fingerpiece extending from said spring-tension to permit of the spring-tension to be forced out of contact with the cap-containing strip. 80

4. A toy-pistol comprising a pair of casing-members secured together to provide a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said casing-members with which the said push-member is normally in engagement, and a spring for controlling said trigger-member. 100

5. A toy-pistol comprising a pair of casing-members secured together to provide 105 a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said casing-members with which the said push-member is normally in engagement, and a spring for controlling said trigger-member 110 associated with a spring-tension within said chamber, said spring-tension having a portion in maintaining contact with the cap-containing strip, but arranged so as not to interfere with the forward movement of the said strip. 115

6. A toy-pistol comprising a pair of casing-members secured together to provide a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said 120

casing-members with which the said push-member is normally in engagement, and a spring for controlling said trigger-member associated with a spring-tension within said chamber, said spring-tension having a portion in maintaining contact with the cap-containing strip, but arranged so as not to interfere with the forward movement of the said strip, and a fingerpiece extending from said spring-tension to permit of the spring-tension to be forced out of contact with the cap-containing strip.

7. A toy-pistol comprising a pair of casing-members secured together to provide a chamber, a trigger-member mounted within said chamber, a hammer-arm pivotally mounted within said chamber, a lift-plate carried by said hammer-arm, and a cap-engaging means pivotally connected with said trigger-member, said cap-engaging means having a portion adapted to engage a raised cap of a cap-containing strip for intermittently feeding said strip in a forward direction, and having another portion adapted to engage said lift-plate for raising said hammer-arm.

8. A toy-pistol comprising a pair of casing-members secured together to provide a chamber, a trigger-member mounted within said chamber, a hammer-arm pivotally mounted within said chamber, a lift-plate carried by said hammer-arm, and a cap-engaging means pivotally connected with said trigger-member, said cap-engaging means having a portion adapted to engage a raised cap of a cap-containing strip for intermittently feeding said strip in a forward direction, and having another portion adapted to engage said lift-plate for raising said hammer-arm, combined with a spring-tension within said chamber, said spring-tension having a portion in maintaining contact with the cap-containing strip, but arranged so as not to interfere with the forward movement of the said strip.

9. A toy-pistol comprising a pair of casing-members secured together to provide a chamber, a trigger-member mounted within said chamber, a hammer-arm pivotally mounted within said chamber, a lift-plate carried by said hammer-arm, and a cap-engaging means pivotally connected with said trigger-member, said cap-engaging means having a portion adapted to engage a raised cap of a cap-containing strip for intermittently feeding said strip in a forward direction, and having another portion adapted to engage said lift-plate for raising said hammer-arm, combined with a spring-tension within said chamber, said spring-tension having a portion in maintaining contact with the cap-containing strip, but arranged so as not to interfere with the forward movement of the said strip.

strip, and a fingerpiece extending from said spring-tension to permit of the spring-tension to be forced out of contact with the cap-containing strip.

10. A toy-pistol comprising a pair of casing-members secured together to provide a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said casing-members with which the said push-member is normally in engagement, a spring for controlling said trigger-member, another pivot-post extending from one of said casing-members, a spring-controlled hammer-arm mounted upon said last-mentioned post, and a lift-plate carried by said hammer-arm with which another portion of said push-member is adapted to be brought in engagement for actuating said hammer-arm.

11. A toy-pistol comprising a pair of casing-members secured together to provide a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said casing-members with which the said push-member is normally in engagement, a spring for controlling said trigger-member, another pivot-post extending from one of said casing-members, a spring-controlled hammer-arm mounted upon said last-mentioned post, and a lift-plate carried by said hammer-arm with which another portion of said push-member is adapted to be brought in engagement for actuating said hammer-arm, combined with a spring-tension within said chamber, said spring-tension having a portion in maintaining contact with the cap-containing strip, but arranged so as not to interfere with the forward movement of the said strip.

12. A toy-pistol comprising a pair of casing-members secured together to provide a chamber, a pivot-post extending from one of said casing members, a trigger-member mounted upon said post, said trigger-member comprising a fingerpiece and an actuating arm, a yoke-shaped push-member oscillatorily connected with said actuating arm, a stop-lug extending from one of said casing-members with which the said push-member is normally in engagement, a spring for controlling said trigger-member, another pivot-post extending from one of said casing-members, a spring-controlled hammer-arm mounted upon said last-mentioned post, and a lift-plate carried by said ham-

mer-arm with which another portion of said push-member is adapted to be brought in engagement for actuating said hammer-arm, combined with a spring-tension within 5 said chamber, said spring-tension having a portion in maintaining contact with the cap-containing strip, but arranged so as not to interfere with the forward movement of the said strip, and a fingerpiece extending 10 from said spring-tension to permit of the spring-tension to be forced out of contact with the cap-containing strip.

13. In a toy-pistol, a pivoted hammer-

arm provided with a hole, and a lift-plate, 15 said lift-plate having a flanged portion in embracing relation with a marginal edge-portion of the hammer-arm, and provided with a tongue extending into the hole of said hammer-arm, all for securing said lift-plate in a fixed position to said hammer-arm.

In testimony that I claim the invention set forth above I have hereunto set my hand this 17th day of July, 1924.

WILLIAM F. GEHRIG.
